UNITED STATES PATENT OFFICE

107,788

DESIGN FOR A SHOE OR SIMILAR ARTICLE

James C. Pape, Larchmont, N. Y.

Application November 24, 1937, Serial No. 73,140

Term of patent 3½ years

To all whom it may concern:

Be it known that I, James C. Pape, a citizen of the United States, residing in Larchmont, in Westchester County, in the State of New York, have invented a new, original, and ornamental Design for a Shoe or Similar Article, of which the following is a specification, reference being had to the accompanying drawing, forming part thereof.

I claim:

The ornamental design for a shoe or similar article, substantially as shown.

JAMES C. PAPE.
